UNITED STATES PATENT OFFICE

2,648,743

EXHAUST PASSAGE AND TRAP MEANS
COEXTENSIVE WITH ARC RUNNERSPhilip L. Taylor, Abington, Mass., assignor to
Allis-Chalmers Manufacturing Company, Milwaukee, Wis.

Application December 28, 1950, Serial No. 203,084

8 Claims. (Cl. 200—147)

1

This invention relates to circuit interrupting devices and more particularly to circuit breakers of the air break type wherein an arc established between separable contacts is transferred along arc runners into an arc extinguishing chute.

The interruption of heavy current power arcs is often accompanied by the emission of a great deal of arc products including incandescent metal particles or other inorganic substances. These particles, if not confined or eliminated from the arc path, reduce the dielectric strength of the surrounding air and thereby increase the time necessary to extinguish the arc or cause failure of the circuit breaker.

In accordance with the invention claimed a new and improved circuit interrupting device is provided comprising relatively movable contacts which are actuated to initiate and elongate an arc therebetween. The arc is then transferred along a pair of spaced arc runners from the region of arc initiation to a region remote therefrom. Trap means may be provided substantially coextensive with all or portions of the arc runners for reducing the free flow of products of arcing from the arcing contacts and arc runner in the general direction of the arc path. Flue or chimney means are arranged substantially coextensive with the arc runners and coextensive with the trap means, if used, to exhaust to atmosphere or a low pressure region the hot gases stripped in whole or in part of the products of arcing.

It is, therefore, one object of the invention to minimize the products of arcing which are propagated into the interrupting zone between the arc runners.

Another object of this invention is to dispose of the products of arcing which are generated at the arc terminals by trapping, bypass or bleed-off means.

Another object of the present invention is to provide a new and improved arc interrupting device in which the hot gases produced by the arc are stripped, in whole or in part, of the products of arcing before being exhausted to atmosphere or a low pressure region.

Another object of this invention is to provide a new and improved arc interrupting device in which the products of arcing and hot gases surrounding the arc runners are cooled and exhausted directly to atmosphere or a low pressure region without passing through an arc deionizing zone which is generally formed of a stack of barrier plates.

2

A further object of this invention is to provide a new and improved arc interrupting device in which a trap means for inhibiting the free flow of the products of arcing to the space between a pair of spaced arc runners is associated with flue means for bleeding off or exhausting directly to atmosphere the products of arcing.

Objects and advantages other than those above set forth will be apparent from the following description when read in connection with the accompanying drawing, in which:

Fig. 1 is a view in cross section, of a magnetic blowout type circuit breaker employing the present invention;

Fig. 2 is a plan view of the arc chute and contact structure shown in Fig. 1;

Fig. 3 is a partial side view on an enlarged scale of the head runner and the trap means and flue means associated therewith; and

Fig. 4 is a cross section of the head runner, trap, and flue means illustrated in Fig. 3 taken along the line IV—IV.

Referring more particularly to the drawings by characters of reference, Fig. 1 illustrates a magnetic blowout type of circuit breaker including as elements thereof a pair of terminal studs 16 and 17 for connecting the circuit breaker to line conductors (not shown). Although in general, circuit breakers of the type considered in Fig. 1 are provided with a plurality of similar pole structures, one for each phase of a polyphase electric circuit, only one such pole structure is shown in the drawing and the circuit breaker will be described in detail as if it was of the single pole unit type.

The circuit interrupter or breaker in Fig. 1 comprises essentially means for opening the circuit to form the interrupting arc and an arc extinguishing structure. Specifically, the circuit opening means comprises a fixed contact assembly supported on an insulator 15 and including a current carrying contact 18, tertiary contacts 19, and arcing contact 20, cooperating with a movable contact 21 comprising current carrying, tertiary and arcing contact combined in a single structure. Movable arcing contact 21 is mounted on a lever 22 which is pivotally mounted at 23 on an extension 24 of the circuit breaker stud 16 and is operated by means of a reciprocally movable rod 25. The operating rod 25 is suitably connected to an actuating mechanism (not shown) for operating the movable contact between closed and open circuit positions. Fig. 1 illustrates the movable contact 21 in closed position. The arcing contacts are

electrically connected to the lower ends of terminal studs 16 and 17. Accordingly, when the breaker is connected in series in a power circuit and the arcing contacts are separated, an arc may be initiated across the gap formed between the contacts.

For the purpose of interrupting this power arc, an arc extinguishing structure, such as an arc chute 30, may be mounted so as to receive the power arc which is under the influence of a magnetic blowout means. The arc chute preferably is disposed directly above the arcing contacts, as shown, when the blowout means act upward, but may be mounted in any other suitable location when the blowout means act in other directions. The switch or arcing contacts and the magnetic blowout structure can assume any preferred form so that a brief description thereof will be sufficient. The magnetic blowout means may comprise a core 31, poles 32, and a coil 33. The latter is electrically connected to the terminal stud 17 and, through a strap 28, to arcing contacts 20 and to a metallic arc runner 34 so that the arc current (as the arc travels along the runner) flows through the blowout coil in a manner well known in the art.

Normally the current is carried in the closed circuit position of the breaker by contact 21 and the spring biased contact 18. While the movable arcing contact 21 is actuated to open circuit position, current is shunted from fixed contact 18 first to fixed contact 19 and then to fixed arcing contact 20. As the arc is drawn by the movable arcing contact 21, the arc terminal on arcing contact 20 is transferred to arc runner 34 which is adjacent to and connected to contact 20 but separated therefrom by a gap 29. The arc terminal is driven across gap 29 to reach a flat side of arc runner 34. When the movable arcing contact 21 approaches a predetermined position in its opening stroke, the other arc terminal transfers from the movable arcing contact 21 to an arc runner 35 which directs the arc into the arc chute 30. When the movable arcing contact 21 parts from contact 19, the flow of current is transferred from contact 19 to contacts 20 through the blowout coil 33. The movable arcing contact 21 subsequently parts from contact 20 to draw an arc. Accordingly, the blowout coil is already energized at the inception of the arc interruption to influence the arc in a well known manner, i. e., to drive it into the arc chute in an expanding loop. It will be apparent to one skilled in the art that the blowout field can be utilized in the most efficient manner by disposing the iron poles 32 so as to cooperate with the blowout coil in the conventional manner outside of the arc chute.

A pair of insulating plates 36 and 37 (more clearly illustrated on an enlarged scale in Figs. 3 and 4) are arranged to extend within the arc receiving end of chute 30 to capture the incandescent particles emitted from the arcing contacts 20 and 21 and the arc runners 34 and 35 as the arc is moved into the arc chute. The end section of the plates 36 and 37 are spaced from arc runners 34 and 35 and arranged substantially coextensive with sections thereof for providing pockets or trap means 38 and 39. The trap means 38 and 39 inhibit the free flow of incandescent particles from the arcing contacts and arc runners to the space surrounding the arc as it is being elongated and introduced into the barrier structure of arc chute 30. As illustrated in Fig. 4, plates 36 and 37 may be spaced apart

from each other to provide a passage therebetween and along the arc runners 34 and 35 for the arc to travel during its movement into and through arc chute 30.

In accordance with the invention claimed, chimney passages or flue means 42 and 43 are arranged substantially coextensive with the arc runners 34 and 35 and the trap means 38 and 39, respectively, for cooling and exhausting to atmosphere or a low pressure region the products of arcing. Flue means 42 and 43 extend from the arcing contacts 20 and 21, that is the region of arc initiation along the arc runners and through the arc chute 30, but outside of a barrier structure 44 to atmosphere. Barrier structure 44 comprises a plurality of spaced insulating plates which are arranged to extend longitudinally of the axis of arc chute 30. The flue means 42 and 43 are arranged with portions thereof substantially coextensive with the arc runners and are preferably also coaxial therewith. Under normal interrupting conditions an arc is initiated immediately upon separation of the arcing contacts 20 and 21. The terminal of the arc on fixed arcing contact 20 is driven across gap 29 over the flat section of arc runner 34 toward the exhaust end of arc chute 30 by the magnetic blowout means and the thermal effect of the arc. As movable arcing contact 21 approaches its fully open position the other terminal of the arc jumps from contact 21 to the flat arc runner 35 and is also driven by the blowout means and the terminal effect of the arc toward the exhaust end of arc chute 30.

Upon initiation of the arc and also during its movement along the arc runners 34 and 35, emission of arc products including incandescent metal particles or other inorganic substances occurs which heretofore were jetted into the area surrounding the elongated arc. These incandescent particles reduce the dielectric strength of the air or other gas surrounding the arc, thereby increasing the possibility of reignition or restriking of the arc after it was extinguished.

By providing flue means 42 and 43 adjacent the point of arc initiation, along the arc runners and through the arc chute to atmosphere, the products of arcing produced in these regions are cooled and the hot gases are exhausted directly to atmosphere before the arcing products and hot gases can lower the dielectric strength of the air surrounding the elongated arc.

The walls forming the flue means 42 and 43 may serve as trap means, or trap means 38 and 39 may be used in addition to the flue means to collect and strip the hot gases of the incandescent products of arcing. Flue means 42 and 43 bypass the stack structure 44 to exhaust the hot gases directly to atmosphere. In order to increase the operating effect of flue means 42 and 43, the cross section area of the flue is made relatively large compared to the cross sectional area of the spaces between adjacent barrier plates 44. Thus, the hot gases and arc products emitted from the arcing contacts, arc runners, and surrounding circuit breaker structure will exhaust to atmosphere through the flue means 42 and 43 and will not have a tendency to diffuse through the barrier structure 44 where they would contaminate the arc path.

Trap means 38 and 39 being disposed immediately adjacent the point of arc inception, the region of initial arcing on the arc runners, and the region where the arc is being elongated by the diverging section of the arc runners inhibit

the free flow of the arcing products from their source, namely the arc terminals toward the zone occupied by the elongated arc. As the power current flows through the arc, the arc products are emitted in all directions from the areas occupied by the arc terminals as they move across the sections of the arc runners. By mounting the sections of trap means 38 and 39 immediately adjacent the arc runners 34 and 35 in the manner described, the rate of flow of arc products into the space between the arc runners where there is potential danger of reignition and restriking is controlled.

Although but one embodiment of the present invention has been illustrated and described, it will be apparent to those skilled in the art that various changes and modifications may be made therein without departing from the spirit of the invention or from the scope of the appended claims.

It is claimed and desired to secure by Letters Patent:

1. An electric circuit interrupter comprising a pair of relatively movable cooperating arcing contacts, means for separating said contacts to initiate and elongate an arc therebetween, an arc chute for receiving the arc at one end thereof, means for transferring the path of said arc from the region of arc initiation to a region within said chute, trap means arranged substantially coextensive with said transfer means for reducing the free flow of products of arcing from said transfer means in the general direction of the arc path, and flue means surrounding said transfer means and said trap means over substantially their entire length for exhausting to atmosphere the hot gases stripped in part of said products of arcing.

2. An electric circuit interrupter comprising a pair of relatively movable cooperating arcing contacts, means for separating said contacts to initiate and elongate an arc therebetween, an arc chute for receiving the arc at one end thereof and exhausting the hot gases at the other end, arc runners for transferring said arc from the region of arc initiation to a region within said chute, trap means arranged adjacent the point of arc inception for reducing the free flow of products of arcing in the general direction of the arc path, and flue means surrounding said arc runners and said trap means over substantially their entire length for exhausting to atmosphere the hot gases stripped at least in part of said products of arcing.

3. An electric circuit interrupter comprising a pair of relatively movable cooperating arcing contacts, means for separating said contacts to initiate and elongate an arc therebetween, an arc chute for receiving the arc at one end thereof and exhausting the hot gases at the other end, arc runners for transferring said arc from the region of arc initiation to a region within said chute, trap means arranged in the region of initial arcing on said arc runners for reducing the free flow of products of arcing in the general direction of the arc path, and flue means surrounding said arc runners and said trap means over substantially their entire length for exhausting to atmosphere the hot gases stripped in part of said products of arcing.

4. An electric circuit interrupter comprising a pair of relatively movable cooperating arcing contacts, means for separating said contacts to initiate and elongate an arc therebetween, an arc chute for receiving the arc at one end there-

of and exhausting the hot gases at the other end, arc runners for transferring said arc from the region of arc initiation to a region within said chute, said arc runners comprising a first section arranged substantially perpendicularly to the direction of relative movement of said contacts and spaced from the region of arc initiation and a second section arranged angularly with respect to said first section for transferring one terminal of said arc from the region of arc initiation to said first section, trap means arranged adjacent the region where the arc is being elongated by said second section of said arc runners for reducing the free flow of products of arcing from said arc runners in the general direction of the arc path, and flue means surrounding said arc runners over substantially their entire length for exhausting to atmosphere the hot gases stripped in part of said products of arcing.

5. An electric circuit interrupter comprising a pair of relatively movable cooperating arcing contacts, means for separating said contacts to initiate and elongate an arc therebetween, an arc chute for receiving the arc at one end thereof and exhausting the hot gases at the other end, a pair of diverging arc runners for elongating and transferring said arc from the region of arc initiation into said chute, trap means arranged substantially coextensive with said diverging arc runners and adjacent the region where the arc is introduced into said arc chute for reducing the free flow of products of arcing from said arc runners in the general direction of the arc path, and flue means surrounding said arc runners over substantially their entire length for exhausting to atmosphere the hot gases stripped in part of said products of arcing.

6. An electric circuit interrupter comprising a pair of relatively movable cooperating arcing contacts, means for separating said contacts to initiate and elongate an arc therebetween, an arc chute for receiving the arc at one end thereof and exhausting the hot gases at the other end comprising a plurality of insulating plates spaced a predetermined distance apart arranged to extend longitudinally of the axis of said chute, means for transferring the path of said arc from the region of arc initiation into the arc receiving end of said chute, and flue means surrounding substantially the entire length of said transfer means for cooling and exhausting to atmosphere the products of arcing, said flue means having a greater cross sectional area than the cross sectional area of the space between adjacent insulating plates.

7. An electric circuit interrupter comprising a pair of relatively movable cooperating arcing contacts, means for separating said contacts to initiate and elongate an arc therebetween, an arc chute for receiving the arc at one end thereof and exhausting the hot gases at the other end, an arc runner for transferring said arc from the region of arc initiation to a region within said chute, and flue means within said chute defining a passageway surrounding said arc runner on all sides over substantially its entire length for cooling and exhausting to atmosphere the products of arcing emitted from said arcing contacts and arc runner.

8. An electric circuit interrupter comprising a pair of relatively movable cooperating arcing contacts, means for separating said contacts to initiate and elongate an arc therebetween, an arc chute for receiving the arc at one end there-

of, means for transferring the path of said arc from the region of arc initiation to a region within said chute, trap means arranged substantially coextensive with said transfer means for reducing the free flow of products of arcing from said transfer means in the general direction of the arc path, and flue means within said chute defining a passageway surrounding said transfer means on all sides over substantially its entire length for cooling and exhausting to atmosphere 10 the products of arcing emitted from said arcing contacts and said transfer means.
